BILGE DRUM ASSEMBLING MACHINE

Armistead Leake, Mobile, Ala., assignor to The
Lerio Corporation, Mobile, Ala.

Application July 28, 1949, Serial No. 107,203

6 Claims. (Cl. 113—22)

1

This invention relates to metal working machines and it has particular reference to a machine especially designed for assembling the pre-formed sections of metallic shipping and storage containers.

A shipping and storage container in the form of a bilge type metal drum such as assembled on the machine herein described forms the subject matter of a co-pending application, Serial No. 107,204, now abandoned. These drums are exceptionally useful as containers for rosin and in current practice, the end sections of the drums, with installed heads, are prefabricated at the factory and shipped in nested relationship to various stills where the sections are joined together by the user. Hitherto, there has been no practical apparatus by which to uniformly produce the bilge seam for joining the sections together and to positively insure against leakage.

It is therefore the primary object of the present invention to provide a machine of such simple construction and mode of operation that it may be used in areas where skilled workmen are unavailable yet accomplishing with untrained workmen results comparable to those of more complicated automatic equipment under the supervision of skilled workmen.

Other objects will become apparent as the description proceeds, taken in connection with the accompanying drawings wherein:

Figure 1 is a top plan view of a machine constructed according to the invention.

Figure 2 is a side elevational view.

Figure 3 is a detail sectional view taken on line 3—3 of Figure 1 and showing the flanging roll.

Figure 4 is a detail sectional view similar to Figure 3, taken on line 4—4 of Figure 1 and showing the flattening roll.

Figure 5 is an enlarged fragmentary view of the anvil on which is performed the final step of collapsing the partially formed bilge seam.

Figure 6 is a fragmentary perspective view showing the flattening roll and operating levers, and

Figure 7 is a fragmentary sectional view of the drum sections showing the form and relationship of the annular flanges thereon.

Continuing with a more detailed description of the drawing, reference numeral 10 denotes a substantially T-shaped platform which is supported in elevated position on legs 11. Supported in turn on the platform 10 by means of a plurality of circularly spaced uprights 12 is an annular mounting 13. This mounting, as illustrated in Figures 3 and 4 has a circumferential recess 14 interiorly of its upper edge which rotatably re-

2

ceives a depending annular flange 15 of a ring gear 16. This flange prevents other than rotative displacement of the ring gear 16 on the mounting 13.

At one point on the periphery of the mounting 13, preferably above the end of the platform 10, there is affixed a bracket 17 on which is mounted a bearing 18. Journaled in this bearing is a shaft 19, carrying on its outer end a crank 20 and on its inner end a pinion 21 whose teeth engage those of the ring gear 16 and is adapted to effect rotation of the ring gear when the crank 20 is operated.

Above the bearing 18 of shaft 19 is disposed another bearing 22. A stub shaft 23 is mounted in this latter bearing and to the inner end of this shaft is affixed an arm 24 which is slightly curved to conform to the curvature of the ring gear. The arm 24 has an integral boss 25 on its upper surface which is bored to provide a socket for a operating lever 26, by which the arm is pivotally moved on its axis 23 as well as inwardly and outwardly, for reasons to be presently explained.

In the end of the arm 24 opposite its pivotal axis is journaled another stub shaft 27. This shaft carries a flattening roller 28, which has an annularly stepped periphery, as revealed in Figures 4 and 6.

Further referring to Figures 4 and 6; the ring gear 16 is provided with an annular recess 29, in which is disposed an anvil ring 30 and it is upon the upper flat surface of this ring that folding operations are performed to produce the head joining the two end sections of a bilge barrel together.

The upper and lower end sections of the barrel or drum are designated as 31 and 32 respectively and are fragmentarily shown in dotted lines in Figures 2 to 5 and in solid lines in Figure 6.

It has been earlier stated that the end sections 31 and 32 are preformed on other machines. The lower section 32 is provided with a flange *a* on its largest end which is slightly wider than the flange *b* on the large end of the companion section 31 and flange *a* has a starting bend *a'* preformed thereon which is adapted to be folded over flange *b*.

To accomplish the foregoing, the lower section 32 is first placed in the machine so that its flange *a* will rest on the upper surface of the anvil ring 30, with the section depending within the gear ring 16. The upper section 31 is then placed so that its flange *b* will rest upon and lie concentric with the flange *a* of the bottom section.

To fold the performed bend *a'* of the flange *a*

as revealed in Figure 3, a flanging or curling roller 33 is mounted on a stub shaft 34, perpendicular to the plane of the ring gear 16. The shaft 34 is suspended from the inner end of an arm 35, pivoted intermediate its ends to an upright 36, the latter being supported by a bracket 37 attached to the perimeter of the mounting 13. A handle 38 is provided on the arm or lever 35 and by virtue of which, the roller 33 is swung in an arc into and out of engagement with the work. The roller 33, as shown in Figure 3, has an annular convex work engaging surface *c* which, when thrust into engagement with the preformed bend *a'* of flange *a* of section 32, folds the bend *a'* downwardly over the narrower flange *b* of the 10 companion section 31, as the crank 20 is operated to revolve the ring gear 16.

When the initial folding operation has been completed, the flattening roller is moved into the position shown in Figures 4 and 6 by manipulating the lever 26. A thrust lever 39, pivoted at 40 to the arm 24 which carries the flattening roller 28, is placed between the rear end of the arm 24 and the bearing 22 of its shaft. This forces the flattening roller inwardly and holds the same 20 against outward displacement while the lever 26 is grasped with one hand, urging the roller against the interengaged flanges while turning the ring gear 16 with the crank 20.

The foregoing operation compresses the bend *a'* of flange *a* against flange *b* firmly and following this operation, the drum is removed from the machine preparatory to performing the final operation of collapsing the interengaged flanges against and in parallelism with the walls of one 30 of the drum sections.

An anvil arm 40 (Figs. 1, 2 and 5) is bolted at 41 to the opposite end of the platform 12 and extends outwardly and upwardly, terminating in the head or anvil 42. The head 43 of the top end section 31 of the drum (Fig. 2) is left with a small central opening 44. This enables the drum to be placed on the arm 40 so that the bilge seam of the drum will rest on the anvil 42, as shown. A gauge plate 45 is secured to the arm 40 adjacent its base 45 by means of slotted brackets 46 and bolts 47, the slots permitting adjustment of the brackets. The gauge plate 45 is engaged by the head 43 of the barrel as it is placed on the arm 40 and thus insures accurate alignment of the backing plate or anvil 42 in relation to the seam. A mallet 48 (Fig. 5) is used to flatten the interengaged flanges *a* and *b* down against the walls of one of the sections 31 or 32 in the manner shown, thus to produce a tight joint.

Manifestly, the construction as shown and described is capable of some modification and such modification as may be construed to fall within the scope and meaning of the appended claims is also considered to be within the spirit and intent of the invention.

What is claimed is:

1. In a machine for assembling the prefabricated end sections of a metal drum having interengageable and preformed annular flanges of unequal widths, the widest of which has an upturned peripheral portion, a circular mounting having an annular recess in its inner periphery, a ring gear having an annular flange depending in said recess, a crank and pinion for rotating said ring gear, an anvil ring disposed in an annular recess in said ring gear and on which is suspended the lower end section of said drum, a flange roller arranged for lateral swinging displacement with respect to the flange of said 75

lower drum section and that of the companion section disposed on said first flange, means for holding said roller in engagement with the upturned peripheral portion of the flange of said lower section to fold said upturned peripheral portion onto the flange of said upper drum end section during rotation of said ring gear to effect interengagement of said flanges, a flattening roller spaced from said flanging roller and mounted for lateral and perpendicular displacement with respect to said section flanges, and means for holding said flattening roller compactedly against the interengaged flanges during rotation of said ring gear.

2. In a machine for joining preformed and flanged end sections of a metal container in which the flange of one section is wider than the flange of the companion section and provided with an upturned peripheral portion, a stationary circular mounting, a ring gear rotatable in said mounting, means for rotating said ring gear, an anvil ring carried by said ring gear adapted to suspend by its flange the lowest of said container sections, the upper container section being adapted to rest on said lower section with its flange in concentric relationship with the flange of said lower section, a flanging roller supported on said mounting for swinging displacement with said flanges and adapted to fold the upturned peripheral portion of the flange of said lowest section onto the flange of the companion container section during rotation of said ring gear, a flattening roller disposed on said mounting for lateral and perpendicular displacement with respect to said end section flanges and means for actuating said flattening roller to compress said flanges and effect close union thereof.

3. In a machine for joining separate preformed end sections of a metal container in which the 40 open ends of the end sections are provided with flanges of unequal widths, the widest of which has an upturned peripheral portion, a stationary mounting, a ring gear in said mounting, means for rotating said ring gear, an anvil ring supported by said ring gear in which the section having the widest flange is suspended by its flange and on which the companion section is disposed with its narrower flange in concentric engagement with the flange of the suspended section, rotatable means movable into engagement with the upturned peripheral portion of the widest of said flanges during rotation of said ring gear to fold said peripheral portion onto the flange of said companion section, and separate 50 means for compressing said flanges together to effect close union thereof.

4. In a machine for joining together preformed end sections of a metal barrel, in which the end sections are provided with end flanges of unequal widths, the widest of said flanges having an upturned peripheral portion, a mounting, an annular rotatable member on said mounting having a gear ring, an anvil ring carried by said gear ring in which is suspended the section having the 60 widest flange, the companion section being disposed with its flange bearing concentrically on the flange of said suspended section, a crank actuated pinion for rotating said gear ring to effect rotation of said barrel section, a roller mounted for swinging movement in relation to said companion barrel section to engage and fold the peripheral portion of the widest flange onto the flange of the companion section during rotation of said sections and vertically movable and 65 rotatable means for compressing the folded por-

tion of said flange into close union with the flange of said companion section.

5. A machine for joining the flanged ends of preformed end sections of a metal container, in which the flanges are of unequal widths, the widest being provided with a preformed annular starting bend, a mounting, a rotatable anvil ring in which is suspended by its flange the section whose flange is the widest, the companion section being inverted to dispose its flange in contiguous and concentric relationship with the flange of said suspended section, a ring gear supporting said anvil ring, means for actuating said ring gear, rotatable means pivotally supported on said mounting for movement laterally with respect to said anvil ring to engage and fold the starting bend of the widest flange inwardly during rotation of said rotatable member and rotatable means carried by said mounting and movable into position for flattening the inwardly turned portion of said flange to effect close union of said flanges.

6. A machine as set forth in claim 5 in which the flange flattening means consists of an arm pivoted for oscillation on a horizontal axis and capable of lateral displacement, a roller carried by one end of the arm and engageable with the said flange, a thrust lever for holding said arm to dispose said roller in operative relation to said flange and means on said arm for urging said roller compressedly against said flange.
